RIDING MOWER

Donald G. Thon and Paul G. Lucht, Cleveland, Ohio,
assignors to MT & D Company, Cleveland, Ohio

Filed Oct. 26, 1960, Ser. No. 62,630

Term of patent 14 years

(Cl. D40—1)

Fig. 1

Fig. 3

FIG. 1 is a front perspective view taken from the right side of a riding mower embodying our new design;

FIG. 2 is a rear perspective view taken from the left side thereof; and

FIG. 3 is a top plan view thereof.

The dominant features of our design reside in the full line portions of the drawing.

We claim:

The ornamental design for a riding mower substantially as shown and described.
